Patented Mar. 30, 1920.

INVENTOR:
ALBERT L. ARENBERG,
BY *Cheever & Cox*
ATTYS.

UNITED STATES PATENT OFFICE.

ALBERT L. ARENBERG, OF CHICAGO, ILLINOIS.

REFLECTOR-SHADE.

1,334,944.

Specification of Letters Patent. Patented Mar. 30, 1920.

Application filed August 18, 1919. Serial No. 318,118.

To all whom it may concern:

Be it known that I, ALBERT L. ARENBERG, a citizen of the United States, residing at Chicago, in the county of Cook and State of Illinois, have invented a certain new and useful Improvement in Reflector-Shades, of which the following is a specification.

My invention relates to reflector shades for electric lighting and similar purposes, but primarily for installations in which a comparatively high power filament lamp is employed, such for example, as are known as "nitrogen" filled or "gas filled" lamps, these usually having the filament concentrated so as to produce, as near as possible, a point source of light. One of the objects of the invention is to provide a reflector shade of this character which shall reflect most of the light downward and outward, but shall at the same time permit a moderate amount to be directed upward toward the ceiling so as to give a cheerful effect to the room in which the fixture is placed. It is my purpose, among other things, to prevent the direct unshaded rays of the lamp from striking the eyes of a person standing at some distance away from the fixture, thus avoiding eye strain to those located where the fixture might readily come within natural range of vision. It is my purpose in connection with the foregoing characteristics to obtain a shade which will reduce to a minimum the absorption of light common in ordinary reflectors, especially where the light rays are forced to pass through one or more layers of glass before reaching their ultimate objective. It is also my purpose to obtain complete diffusion so as to avoid all sharply defined shadows. In connection with the foregoing, another object is to produce a fixture which shall have a pleasing appearance. Still another object is to provide a shade which shall be dust-proof, thus keeping it efficient in transmitting and reflecting light and eliminating the factor of attendance to keep it clean. In carrying out these objects, according to the particular design illustrated, the entire device is made of a single piece of glass or similar material.

I obtain my objects by the construction illustrated in the accompanying drawing which is an axial section of a device embodying my invention, the same being shown with a lamp and a shade holder in position.

In the form illustrated, my shade is supported by a shade holder 1 having the usual set screws 2. Said shade holder is suspended by a chain 3 or similar suspending means and is provided with a socket 4 for the lamp 5. In this case the lamp has a filament 6 which is concentrated in a comparatively small compass so as to afford practically a point source.

Referring now to the parts more intimately concerned with the invention, the reflector shade has a central chamber 10 having approximately cylindrical sides 11 and a convex closed bottom 12. In the preferred form, illustrated, the entire device is made of a single piece of clear glass covered, over certain areas, with enamel of one density or another as will be hereinafter pointed out. In the illustrated case, a layer 13 of enamel of single density covers the entire bottom of the central chamber up to a point almost level with the filament 6. The remaining portion of the central chamber is of clear glass, the result being that the rays which project appreciably below the level of the filament are partially transmitted and are partially reflected upward and laterally. Such of the downward and laterally projecting rays as are transmitted produce a moderate lighting effect on the area beneath, thus protecting the eyes against a too strong light and at the same time preventing them from seeing a definite point source of light. These rays are diffused and softened and impart a cheerful appearance to the central portion of the fixture, but at the same time avoid eye strain. Those rays that pass through the clear portion 11 and constitute perhaps half of the total issuing from the filament, strike the reflecting surface 22, hereinafter mentioned. The rays that pass more or less directly upward are reflected by means of an opaque deflector 14 which may be made of enameled steel.

Arching radially outward and downward from the top of the cylindrical walls 11 of the central chamber is a dome-like portion 16, the underside being concave and swinging downward and outward to a point 17 which is, in the present design, approximately on a level with the lower end of the central chamber. At this point the shade rounds outward and thence upward to form an outer wall 18 which by preference is approximately cylindrical and rises to a height 110

appreciably greater than the level of the upper end of the central chamber. The wall 18 and the adjacent portion of the inner dome 16 form a hollow annular flange portion for the shade. Extending inward and upward from the top of the annular wall 18 is a portion 19 which for convenience may be termed the outer dome or "roof" of the shade. This roof portion is shown as being approximately frusto conical although it may be more or less rounded if desired. It terminates in a collar 20 adapted to seat upon the set screws 2.

The lower edge 17 is low enough to intercept such light rays as pass through the wall 11 over the upper edge of the enamel 18. This prevents direct undimmed rays from being directly visible to persons standing at some distance away from the fixture but within the range thereof.

On the under side of the lower dome 16 is a layer of enamel 22 of double density. This receives and reflects downward and moderately outward, nearly all the rays 25 passing through the clear glass portion 11. Some of these rays, however, are transmitted, and diffusely illuminate the ceiling. This causes the major portion of light to be confined within a proper area and at the same time diffused so as to avoid any sharp 30 images of the light source and to avoid any sharp shadows of objects in the room.

The outer side wall 18 has a layer 23 of single density enamel which is capable of 35 dimming the light rays passing through it but at the same time imparting a cheerful, attractive appearance to the fixture. But the portion of light not transmitted is largely reflected back into the interior of 40 the shade where it will take the course of the other rays there.

The upper dome or roof 19 is preferably of clear glass and thus transmits the light which comes to it; but in view of the presence of the deflector 14 and enamel 22, only 45 enough light will reach it to throw a moderate quantity of light onto the ceiling. A dark ceiling is cheerless and unattractive and with my device this condition is avoided 50 and the ceiling lighted to a proper degree.

It will be evident that in practice not only will the entire shade and the adjacent area of the ceiling present a luminous appearance, but a large portion of the emanation 55 will be reserved for the lighting of a reasonable amount of area beneath. This is where the bulk of the light is wanted, and this is where it is directed by my device. Nevertheless, there is no position, in practice, where a person will receive rays direct 60 and undimmed from the light source. Hence, the effect is grateful to the eyes and the fixture is also efficient in directing the rays where most beneficial.

65 I wish to point out that in the preferred

construction, as illustrated, the convenient and natural place for the enamel is on the lower rather than the upper (internal) surface of the lower dome 16, and the enamel, when so placed, and as I have placed it, 70 performs its reflecting function before and not after the rays have penetrated the glass on which the enamel is mounted. In fact, the layers 22 largely prevent the rays from reaching the glass 16 and hence avoid the 75 absorption, and consequent waste of light which occurs whenever light passes through even the clearest of glass. Thus my device is not only attractive and throws the light where needed, but actually reduces the loss 80 of energy to a minimum.

Another important advantage possessed by my shade is that it is dust proof. There is no opening at the bottom and if the shade holder is properly fitted, no dust can 85 enter. The result is that no cleaning is necessary, practically speaking, and the light is never dimmed by having to pass through a layer of dust.

Having thus described my invention, 90 what I claim as new and desire to secure by Letters Patent, is:—

1. A lighting unit having a central glass chamber adapted to contain a source of light, said chamber being adapted to substantially inclose the source of light and the upper portion being of clear glass, said chamber having an integral, glass, annular extension at the top extending outward and located in position to be struck by the light 95 passing through the upper, clear glass portion of the central chamber, said extension having a substance applied to its surface on the side nearest the light source, said substance being capable of transmitting a portion of the light, but adapted to reflect the 100 major portion of said light.

2. A reflector shade having a central chamber adapted to contain a source of light, an inner dome extending outward and 110 downward from the top of the central chamber and an outer dome arranged above the inner dome and spaced from it, the outer dome having at its periphery a depending flange connecting with the periphery of the 115 inner dome, the upper portion of the central chamber being adapted to transmit practically all of the light rays striking it and the inner dome being adapted to reflect downward and outward the rays which 120 reach it through the said upper portion of the central chamber.

3. A lighting unit having a central glass chamber adapted to contain a source of light, the upper portion of the chamber 125 being of clear glass, a glass extension integral with the upper end of the central chamber and extending outward and located in position to be struck by the light passing through the upper clear glass portion of 130

the central chamber, and a glass dome above said extension, integral with it at the annular rim thereof, said dome being adapted to transmit some of the light rays striking it from the inside, and enamel applied to the underside of said extension, said enamel being adapted to reflect the major portion

of the light striking it and to transmit a small portion of such light to thereby impart subdued illumination to the upper dome.

In witness whereof I have hereunto subscribed my name.

ALBERT L. ARENBERG.
